UNITED STATES PATENT OFFICE.

ANTON WELLERT, OF BINGHAMTON, NEW YORK.

VEHICLE SIGNAL.

Application filed April 29, 1926. Serial No. 105,380.

My invention relates to improvements in vehicle signals particularly adapted for indicating the movements of the vehicle when in operation.

5 It is the primary object of the invention to provide a signal designed to simulate a human arm and hand, having means to move the hand to various positions, to indicate to the drivers of other vehicles the direction 10 in which the vehicle is about to turn.

A further object of the invention is to provide a signal movable to various positions which is actuated by a single operating medium, thereby, simplifying its operation.

15 Another object of the invention is to provide a device of the above mentioned character which is simple and durable in construction, reliable and efficient in operation and inexpensive to manufacture.

20 Other objects and advantages of the invention will be apparent during the course of the following description.

In the accompanying drawing, forming a part of this specification and in which like numerals are employed to designate like parts throughout the same,

25 Fig. 1 is a side elevation of the device showing the position of the signal when fully extended,

30 Fig. 2 is a longitudinal sectional view showing the position of the signal when partially extended,

Fig. 3 is a similar view to Fig. 2, showing another position of the signal, and,

35 Fig. 4 is a detail sectional view taken on lines 4-4 of Fig. 1.

In the drawing, wherein for the purpose of illustration I have shown a preferred embodiment of my invention, the numeral 40 5, denotes a casing of oval contour, adapted to be mounted on the side of a vehicle body 6, in an upright position and having a mirror 7 on one side. The casing is supported from the side of the vehicle body by a bracket 45 8, attached to the rear wall of the casing, as at 9.

A toggle frame denoted in general by the numeral 10, has two end links 11, pivotally connected to the ends of the innermost toggle links 10' and 11', which are crossed but not pivoted together, and their free ends are pivotally connected to the lugs 12, extending from the rear wall of the casing adjacent the top and bottom thereof. The toggle is 50 adapted to extend through the front of the casing which is open, as at 13, and a signal

formed of two folded sections 14, in the shape of a hand is connected to the outer end of the frame in a manner to be herein-after described.

60 The links of the toggle, which extend beyond the casing are formed from flat metal plates 15, so when the toggle is extended it will simulate an arm. In order that the signal will assume various positions, with 65 respect to the toggle, the end of the link 16 is shorter than the end of the link 17 and is pivotally connected to the end of the link 18 which is pivotally connected at its center to the link 19, the innermost end of the latter 70 being shorter than the end of the link 18 and connected to the end of the link 17. The outer ends of the links 18 and 19 are pivotally connected to the ends of the short links 20 and 21, the link 20 being fixedly attached, as at 22, to the strip 23 connecting the two 75 sections of the signal 14 which enclose the outer links. The free ends of the links 20 and 21 are pivotally connected together, as at 24.

80 This arrangement of the toggle links provides a mechanical movement, which when the toggle frame is fully extended will swing the signal in an upward position, at right angles to the frame, as shown in Fig. 1, or when partially extended as shown in Fig. 2, will support the signal in a horizontal position and when in the position shown in Fig. 3, will deflect the signal in a downward direction. In order that the toggle 85 frame may be fully retracted within the casing it will be observed that the two innermost toggle links have their outer ends offset outwardly, as at 24', and the outermost toggle links 18 and 19 have their outer ends offset inwardly, as at 25', disposing the intermediate links 16 and 17 in spaced relation, so when the frame is collapsed the end links will fold between the intermediate toggle links. A majority of the links have their 90 longitudinal edges rabbeted, as at 25, to allow for the passing of the pivotal connections between the links when collapsing the frame and when the frame is fully retracted, the signal will be completely enveloped by the casing.

100 The signal is operated through on operating rod 26 pivotally connected at its outer end to the pivotal connection 27 between the two innermost toggle links. The rod extends through an opening 28 in the rear wall of the casing 5 and the aligned opening 105 110

29 in the vehicle body, having its inner end enclosed in the tube 30, attached to the inside of the vehicle body, as at 31. The bottom of the tube is open for a portion of its length, as at 32, to receive the operating handle 33, pivotally mounted on the inner end of the rod 26, as at 34, and having a plunger 35 mounted in the bore 36, adapted to be pressed into engagement with one 5 of the sides of the block 37 fixedly mounted on the rod 26, by the spring 38. The side of the tube, at its end is notched, as at 39, to provide shoulders 40 which serve as a stop for the operating handle. When the 10 handle is in the position shown in Fig. 1, the toggle frame is fully extended and when it is desired to move the signal to the position indicated in Fig. 2, the handle is drawn inwardly and turned to engage the 15 intermediate shoulder and when the handle is moved to engage the end of the tube, as in Fig. 3, the signal will be deflected downwardly.

20 A lamp casing 41 carrying a bulb 41' is mounted on the top of the casing 5 having side lenses 42 and a front lens 43, focused on the signal, so that it will be readily visible at night. One of the side lenses has "Slow" painted thereon, as shown in Fig. 1, 25 and the wires 44 leading from the lamp extend through the body of the vehicle, being connected to a switch, not shown, which is in circuit with the lighting system of the vehicle, the switch being of a well known 30 type adapted to be actuated by the brake pedal of the vehicle.

35 In view of the foregoing the operation of the signal is obvious, it being understood that the different positions of the signal 40 will indicate different movements of the vehicle. The signal is designed so it will clearly and unmistakably indicate the movements of the vehicle and is particularly adapted for use on closed vehicles.

45 It is to be understood that the form of my invention herewith shown and described is to be taken as a preferred example of the same and that certain changes in the shape, size and arrangement of the parts 50 may be made without departing from the spirit of the invention or the scope of the subjoined claims.

Having thus described my invention, I claim:

55 1. A vehicle signal of the character described, comprising a casing, a series of toggle links mounted within said casing adapted to extend therefrom, said links being composed of relative wide plates which 60 when extended will simulate an arm, said plates being rabbeted along their edges to permit contraction of the links, and a signal mounted on the outermost end of said links.

2. A vehicle signal of the character described comprising a casing, a series of toggle links mounted within said casing composed of relative wide plates adapted to simulate an arm when the links are extended, a signal composed of folded sections, a 65 pair of links pivoted together at one end, one of said links being fixedly attached to the jointure between the sections of the signal and the free ends of said links being respectively pivoted to the free ends of the 70 outermost toggle links, the cooperating ends of said outermost toggle links being of various lengths, whereby the angular position of the signal with respect to the toggle links will be changed through extension 75 and retraction of said toggle links, said links having their edges rabbeted to permit contraction and operating means controlling said toggle links.

3. A vehicle signal of the character described comprising a casing, an arm composed of a series of toggle links mounted within said casing, a signal, a pair of links pivoted together at one end, one of said links being fixedly attached to said signal 80 and the free ends of said links being respectively pivoted to the free ends of the outermost toggle links, the opposite ends of the two outermost toggle links being of different lengths, whereby the signal will 85 be moved at right angles to the arm when the latter is fully extended, said signal being movable to different angular positions through the action of the toggle links when the arm is partially extended and operating 90 means controlling the extension and retraction of said toggle links.

4. A vehicle signal of the character described comprising a casing, an arm composed of a series of toggle links, a pair of crossed links pivoted within said casing having their free ends respectively pivoted to the ends of the innermost toggle links, a signal composed of folded sections, a 105 pair of links pivoted together at one end, one of said links being fixedly attached to the jointure between the sections of the signal and the free ends of said links being respectively pivoted to the free ends of the outermost toggle links, the opposite ends of said outermost toggle links being of different lengths, whereby the signal will be moved at right angles to the arm when the latter is fully extended, said signal being 110 movable to different positions through the action of the toggle links when the arm is partially retracted, and operating means controlling the extension and retraction of said toggle links.

115 In testimony whereof I affix my signature.

ANTON WELLERT.
